UNITED STATES PATENT OFFICE.

MILTON H. MCNAIR, OF MEADVILLE, PENNSYLVANIA.

BUTTON-FASTENER.

SPECIFICATION forming part of Letters Patent No. 295,575, dated March 25, 1884.

Application filed July 6, 1883. (No model.)

To all whom it may concern:

Be it known that I, MILTON H. MCNAIR, a citizen of the United States, residing at Meadville, in the county of Crawford and State of Pennsylvania, have invented a new and useful 5 Metallic Button-Fastening, of which the following is a specification.

My invention relates to an improvement in metallic button-fastenings constructed of a 10 single wire formed into a triangular loop, as shown by the accompanying drawings.

Figure 1 is a perspective view of my metallic button-fastening attached to the material. Fig. 2 is a plan view, showing the loop before 15 the prongs are formed. Fig. 3 is a perspective view after the prongs are formed. Fig. 4 is a plan view after the prongs are formed into hooks; Fig. 5, a perspective view after 20 the hooks are formed, and showing the turning of the button by the dotted lines.

Similar letters and figures refer to similar parts.

A is the triangular loop, as shown in Fig. 2. The object of this triangular loop is, when 25 the button-hook is applied it allows the button to turn part way around in the curved neck C, as shown in Fig. 5, thus preventing the disarrangement of the fastening or hooks. This loop is bent at a right angle at 1, to form two 30 curved prongs, B, as shown in Fig. 3. The object of the curve of these prongs is that when

they are forced through the material and bent down on the under side of the material the points press up as pressure is brought on the button, thus securing perfect safety from the 35 points coming in contact with the foot or body. The prongs B, after being forced through the material, are bent down parallel, as shown in Fig. 4, clamping the material at 2, and thus forming hooks, as shown in Figs. 1 and 5. 40

The triangular loop terminating in two hooks gives greater strength, as the strain is divided, being both direct and from each side.

Having described my invention, I would not be understood as claiming a metallic button-fastening, broadly, nor such a fastening made 45 of wire. I am aware that such have been in use. These do not embrace the features of my improvement.

I claim—

The improved button-fastener herein described, consisting of a piece of wire bent to form the loop A, and curved pointed prongs B, adapted to underlie the material and form hooks whose points are embedded in the 50 material when strain is brought upon the button, all substantially as described.

MILTON H. MCNAIR.
